MOP WRINGER

Juan Gunfaus, Av. J. de Sagrera, S/N.,
Tarrasa, Barcelona, Spain

Filed Apr. 3, 1969, Ser. No. 16,564

Term of patent 14 years

Int. Cl. D7—06

U.S. Cl. D49—29

FIG. 1

FIG. 2

FIG. 3

FIG. 4

FIG. 5

FIG. 1 is a front view of this mop wringer showing my new design;

FIG. 2 is a rear view of this mop wringer;

FIG. 3 is a side view;

FIG. 4 is a top plan view, and

FIG. 5 is a bottom plan view of this mop wringer showing my new design.

The side view of this mop wringer not shown in the drawing has an appearance identical with the appearance of the side view shown in FIG. 3 of the drawing.

I claim:

The ornamental design for a mop wringer, substantially as shown and described.
